UNITED STATES PATENT OFFICE.

MARY T. CONFREY, OF INDIANAPOLIS, INDIANA.

HAT-PIN.

996,003.

Specification of Letters Patent. Patented June 20, 1911.

Application filed November 29, 1909. Serial No. 530,496.

To all whom it may concern:

Be it known that I, MARY T. CONFREY, a citizen of the United States, residing at Indianapolis, in the county of Marion and State of Indiana, have invented a certain new and useful Hat-Pin, of which the following is a specification.

Common hat pins are not adjustable as to length, and therefore are not suitable for use with all the varying sizes of headgear. If long enough to be useful with very large head coverings, the points of the pins project through to an objectionable extent, while if short enough to be conveniently used with the smaller head coverings the same hat pins cannot efficiently be used with the larger head coverings. Then, too, when the points project through to a considerable extent there is an element of danger to other persons in the immediate vicinity, who are likely to get their eyes put out or faces scratched by the projecting points.

It is the object of my present invention to produce a hat pin which shall avoid these objections.

Referring to the accompanying drawings, which are made a part hereof, and on which similar reference characters indicate similar parts, Figure 1 is a view of a hat pin embodying my present invention; Fig. 2 a sectional view thereof on an enlarged scale, the central portion being broken away to permit the scale desired; Fig. 3 a detail sectional view similar to a portion of Fig. 2 but on a still further enlarged scale, and showing the fastening device in unfastened position, and Fig. 4 a transverse sectional view as seen when looking downwardly from the broken line 4-4 in Fig. 3.

My improved hat pin consists of three principal parts. The central or main part consists of a pin body, a considerable portion, 15, of which is very similar to the bodies of the pins now commonly in use. That portion, 16, however, near the head of the pin is tubular in form, and interiorly screw-threaded. Into this interiorly screw-threaded portion the body, 17, of the upper part extends, said body being correspondingly exteriorly screw-threaded. This last mentioned part carries an ordinary head, 18.

Upon the point of the portion 15 is a second and removable head, 19, containing a fastening device, 20, by which it may be securely fastened to the point of the pin, after 55 said pin has been inserted to operative position. This second and removable head covers the otherwise sharp point of the pin, and renders it harmless.

In operation, the hat pin is adjusted to the 60 desired length by screwing the portion 17 into or out of the portion 16 until the desired length is obtained. This may for the most part be done before the pin is inserted in place, but if after it is inserted any additional adjustment is desired, that is easily done. After the pin is inserted in place then the removable head 19 is pushed over the point, and the fastener 20 operated, which holds it firmly in place. Any desired 65 form of fastener may be employed, but I have shown a small lever, having a cam end which impinges upon the side of the pin near its point when turned down to the position indicated in Fig. 2 of the drawing. A 70 slight depression or small annular groove, 21, may be formed in the pin where the cam comes in contact therewith for purposes of additional security, as shown.

Having thus fully described my said invention, what I claim as new, and desire to secure by Letters Patent is:—

1. The combination, in a hat pin, of a body part having a tubular interiorly screw-threaded portion, and a head part having a 85 shank portion exteriorly screw-threaded and adapted to enter the interiorly screw-threaded portion of the body part.

2. The combination, in a hat pin, of two portions one provided with a head and the 90 other provided with a point, said two portions being telescopically united, whereby the length of the hat pin may be varied as desired.

In witness whereof, I, have hereunto set 95 my hand and seal at Indianapolis, Indiana, this twenty-seventh day of November, A. D. one thousand nine hundred and nine.

MARY T. CONFREY. [L. S.]
